UNITED STATES PATENT OFFICE.

GEORGE M. MORRIS, OF RICHMOND, CALIFORNIA.

BOW GUIDE FOR VIOLINS AND THE LIKE.

Application filed September 8, 1924. Serial No. 736,680.

My invention relates to a device for insuring a proper longitudinal positioning of the bow on the strings of a violin or the like.

An object of the invention is to provide a device of the character described which will not interfere with the playing or tone of the instrument to be played.

Another object of the invention is to provide a device of the character described which may be simply rendered inoperative without removal of the device.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a longitudinal sectional view of a violin equipped with the device of my invention.

Figure 2 is a transverse sectional view taken on the line 2-2 in Figure 1.

Figure 3 is a perspective view of the embodiment of my invention shown in Figures 1 and 2.

Figure 4 is a perspective view of another embodiment of my invention.

Teachers of the violin, and like instruments, have heretofore experienced much difficulty in imparting correct bowing habits to the pupils, owing to the fact that the bowing and fingering must be taught simultaneously. The difficulty arises on account of the fact that while the bow is preferably used over a limited portion of the strings, the pupil is inclined to allow it to move onto other portions of the strings to thus produce faulty handling of the bow, since the attention of the pupil is chiefly concentrated on the fingering. To obviate the foregoing and other difficulties in the teaching of the violin, I have provided a bow-guiding device which prevents the displacement of the bow from its proper position on the strings and at the same time does not affect the tone or appreciably affect the appearance of the violin.

As here shown, the bowing-guide of my invention comprises a support member 6 car-

ried on the violin body 7 and on which is mounted suitable guide members 8. As here shown, the support 6 is positioned in space: relation from and between the strings 9 and belly 11, and between the bridge 12 and the end 13 of the fingerboard 14 of the violin. The support 6 is preferably held positioned by means of oppositely disposed extensions 16 arranged to grip the edges 17 of the belly 11 at the waist portion 18 of the violin. In the present embodiment, the extensions 16 are arranged with slidably engaged portions 21 and 22, the former being preferably formed integral with the member 6. The portion 22 is normally held in retracted position with relation to the portion 21 by means of helical springs 23 extending between hooks 24, which are preferably provided on the under side of the extension portions 22, with cooperating hooks 26, the latter being provided on the under side of the support 6. The portions 22 are provided with violin engaging portions 27 arranged to fit the belly edges 17, the bearing surfaces of the portions 27 being preferably provided with pads 28 of felt or some other sound insulating substance. In this manner, the device is arranged to be resiliently and removably mounted on the violin and since it is mounted on the edge of the violin belly, does not affect the tone of the instrument.

The guide members 8 may be formed and mounted in any desired manner. As here shown, the guide members comprise pairs of 90 guide posts 29 mounted on rotatable members 30, the latter being pivotally carried on the under side of the member 6. The members 8 are spaced apart longitudinally of the violin strings to define a bow guideway of 95 desired width and are of such length that when erected they will engage the back of the bow, the posts 29 being positioned to protrude between the strings without contacting with them. Slots 32 are provided 100 in the support member 6 so that the posts 29 may be swung downwardly below the plane of the strings to allow the playing of the instrument without use of the device or the removal thereof, it being noted that this 105 folded position of the posts is indicated in dotted lines in Figure 3.

In the embodiment shown in Figure 4, the support member 41 is in the form of a plate having opposite edges 42 turned down 110 and arranged to receive the threaded ends 43 of U shaped violin engaging extensions

44, the latter being shaped at their outer ends to fit the belly edge of the violin. Adjustment to fit the violin is simply accomplished by the use of cooperating nuts 45 50 on the ends 43 of the extensions 44 disposed on opposite sides of the edges 42. The guide members 46 are also U shaped and are arranged to fit sockets 47 provided in the face of the member 41, the post portions 10 48 of the members 45 being arranged to pass between the violin strings, and the connecting portions 49 of the members being arranged to be disposed above and transversely of the strings when the members 45 are in 15 position. In this manner, this embodiment may be rendered inoperative by simply removing the guide members from the sockets.

I claim:

1. A bow-guide for a violin or the like 20 comprising a supporting member, means for releasably mounting said member in spaced relation from and over the midportion of the belly of the violin between the bridge and finger board, and a guide member disposed 25 placeably mounted on said supporting member.

2. A bow-guide for a violin or the like comprising a supporting member, means for mounting said member on and between opposite edges of the belly of the violin at the 30 waist thereof and between the strings and said belly, and a guide member displaceably carried on said supporting member.

3. A bow-guiding means for a violin or 35 the like comprising a supporting member, means for releasably mounting said member on the side edges of the violin and disposed between the belly and strings thereof, and members displaceably carried by said supporting member defining a guide fork for 40 said bow between them.

4. A bow-guide for a violin or the like 45 comprising a supporting member, means engageable with opposite side edges of the violin belly for mounting said member between the belly and strings of the violin

and between the bridge and finger board thereof, and longitudinally disposed displaceable guide members carried by said supporting member and defining a guideway 50 for said bow between them.

5. A bow-guide for a violin or the like comprising a supporting member, means for mounting said member between the strings and belly of the violin, and guide members 55 pivotally secured to said supporting member and cooperating when in extended position to limit the movement of the bow toward either end of said strings.

6. A bow-guide for a violin or the like 60 comprising a supporting member, means for mounting said member on said violin, longitudinally disposed guide members pivotally secured to said supporting members and defining when in extended position a guideway 65 between them to limit the movement of the bow toward either end of said strings and permitting when in folded position free longitudinal movement of the bow along 70 said strings.

7. A bow-guide for a violin or the like, comprising a supporting member, means for mounting said member between the belly and strings of the violin and between the bridge and fingerboard thereof, and longitudinally 75 disposed independently displaceable guide members mounted on said member and cooperating to define a transversely extending guideway for a bow when operatively disposed on the member. 80

8. A bow-guide for a violin or the like, comprising a supporting member, means for mounting said member on the belly of the violin and in a position below the strings thereof, and a guide member mounted on 85 said supporting member and movable to a position above said strings from a position therebelow, and vice versa.

In testimony whereof, I have hereunto set my hand at Oakland, California, this 31st 90 day of July, 1924.

GEORGE M. MORRIS.
